L. MARX

FIGURE TOY

Filed March 21, 1923

UNITED STATES PATENT OFFICE.

LOUIS MARX, OF NEW YORK, N. Y.

FIGURE TOY.

Application filed March 21, 1923. Serial No. 626,535.

To all whom it may concern:

Be it known that I, LOUIS MARX, a citizen of the United States, and resident of New York city, in the county of New York and State of New York, have invented certain new and useful Improvements in Figure Toys, of which the following is a specification.

This invention relates to a toy amusement device, and more particularly to an amusement device adapted to be operated for simulating a syncopated or "jazz" drummer in action.

The principal objects of my present invention may be said to include the provision of a toy amusement device in which a toy figure is provided with a simulated drum outfit adapted to be mechanically operated to produce a true and life-like simulation or 20 characterization of a drummer playing a syncopated selection; the further provision of a toy amusement device of this nature in which is provided a toy figure adapted to be set in motion, the said figure being associated with a snare drum, a bass drum and a trap implement, all adapted to be coordinately operated by and with the movement of the figure to produce an action in striking resemblance to a natural drumming performance; and the further provision of a 30 device of this character in which the parts are arranged in a pleasing and attractive fashion and operated in a simple manner to produce a neat and inexpensive toy.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention, and in which:

Fig. 1 is a perspective view of the drummer toy amusement device.

Fig. 2 is a plan view taken in cross-section on the line 2—2, Figure 1.

Fig. 3 is a vertical elevational view taken in cross-section on the line 3—3, Fig. 2, and

Fig. 4 is a fragmentary vertical elevation taken in cross-section on the line 4—4, Fig. 3.

Referring now more in detail to the draw-

ings, the toy amusement device of my present invention comprises generically the figure A, a drum outfit generally designated as 55 B associated therewith, all arranged on a stage C, which constructionally may comprise a cover or closure for a casing D, the said figure being adapted to be set into action by motor mechanism housed by the said 60 casing D for the simulated rendition of a preferably syncopated or "jazz" drumming act.

In the preferred construction, the drum outfit B includes a representation of a bass 65 drum b, a simulated snare drum b', and a simulated trap implement, such for example as the cymbal device b², the said drums and the trap implement being adapted to be operated by and in harmony with the movement 70 of the figure A.

For producing a harmonious and compact, as well as pleasing grouping of the parts of the device, the bass drum b is arranged on the platform C with the cylindrical body 75 thereof resting in fixed position on the platform, and the figure A is arranged in the seated position on the said bass drum, the snare drum b' being carried by the figure A and located in a position to be operated 80 by the movement of the hands of the figure, as will be detailed further hereinafter, the cymbal device b² being arranged as shown at the front end of the platform and in position to be operated by the movement of one 85 of the legs of the figure, as will presently appear.

For operating or beating the bass drum b, there is provided a drum stick 10 movable in relation to the drum b, the said drum stick 90 conveniently comprising a bell crank lever pivotally journaled in a depending bracket 11 fixed to the platform C, the lower arm 12 of the bell crank lever being adapted to be oscillated for producing an oscillation of the 95 drum stick against the side of the drum b.

For operating or beating the snare drum b', I preferably provide a pair of drum sticks 13 and 14 which may be carried by or in the hands 15 and 16 of the figure, the said 100 hands being conveniently formed integrally with the arms 17 and 18 which are oscillatably mounted on the body 19 of the figure, the said arms being to this end fixedly car-

ried by the rock shafts 20 and 21 journalled in opposite sides of the figure, as clearly shown in Fig. 4 of the drawings.

To produce a life-like and natural simulation of a drumming action, the drumsticks 13 and 14 are moved in beating alternation on the drum b' , and to this end means are provided for oscillating the arms 17 and 18 in opposition or alternation, as indicated by the arrows in Fig. 1 of the drawings, the said means preferably comprising the crank arms 22 and 23 which may be formed integrally with the rock shafts 20 and 21, the said crank arms being relatively angularly spaced substantially 180° , so that when the crank arms are both moved in one direction the arms 17 and 18 are moved in opposition. For moving the crank arms 22 and 23, I provide a forked member 24 which is arranged for reciprocating motion in the body 19 of the figure, the said forked member terminating in the tines 25 and 26 which are looped at their ends for loosely engaging the corresponding loops of the crank arms, as clearly shown at 27 and 28 in the figures.

The cymbal device b^2 may conveniently comprise a pair of cymbals 29 and 30, the cymbal 29 being loosely attached to the stage or platform C, and the cymbal 30 being loosely attached to and carried by a foot 31 forming part of the loosely jointed leg members 32, the upper leg member being mounted for rocking or oscillating movement on the pivot or shaft 33 journalled in the body 19 of the figure, the construction being such that upon rocking or oscillating movement of the upper leg member 32, the cymbal device will be operated.

For operating all the instruments in synchronization and harmony, there is provided a motor mechanism in the casing D, the said motor mechanism preferably comprising a spring motor 34 adapted to be wound or energized by a winding key 35, the said motor being provided with an attached gear 36 for transmitting motion to a combined gear and pinion 37 fixed to a shaft 38 journalled in a suitable bracket 39 fixed to the casing body, the said shaft being provided with a crank arm portion 40 which engages a loop 41 forming the bottom end of an operating rod 42, the said rod pivotally engaging at its upper end a cross rod 43 which is attached to the upper leg member 32 at a point to the rear of the pivot or shaft 33 thereof, the bottom end of the forked member 24 also pivotally engaging the cross rod 43, as is clearly shown for example in Figs. 3 and 4 of the drawings. By means of this construction, it will be seen that when the motor 34 unwinds, the operating rod 42 is reciprocated to oscillate the leg member 32 and to reciprocate the forked member 24 for moving the arms of

the figure, the trap implement and the snare drum being thereby operated in synchronism. In the preferred construction the drum stick 10 is also operated by the reciprocation of the rod 42, and to this end the outer end of the arm 12 of the drum stick is provided with a loop 44 which embraces the rod 42 and which is engaged by a member 45 fixed to the rod 42, the arrangement being such that when the rod is moved to ascended position, the drum stick 10 is moved out of engagement with the drum as indicated in Fig. 1; and when the rod is moved to descended position, the drum stick 10 moves to contact with the drum, as is shown for example in Fig. 4 of the drawings.

The motor mechanism housed by the casing D is preferably provided with a start and stop device, which may consist of a system of gearing generally designated as 46 comprising gears loosely mounted on the shaft 39 and on shaft 47, the said gearing being driven by the gear 37 for producing a multiplied motion of a braking gear 48 which is adapted to be engaged and disengaged by a braking lever 49 for producing a stopping and starting respectively of the motor mechanism.

In the preferred construction, there is provided a sounding element housed by the casing D, which sounding element is operated in synchronism with the musical instruments, the said sounding element preferably comprising a bell 50 which may be fixed to the bottom of the casing D and a bell hammer 51 rockably mounted on a shaft 52 in an upstanding bracket 53, the said bell hammer being gravitationally movable in contact with the bell 50 and being movable out of contact therewith by means of an oppositely winged member 54 fixedly carried by the shaft 38, the said winged member rotating in the direction, as shown in Fig. 3 of the drawings, for engaging the arm 55 of the bell hammer lever 51. It will be noted that the arrangement of the parts is such that the bell hammer strikes the bell twice in each revolution of the shaft 38, so that the bell is sounded at the alternate operations of the drum stick 10 and the cymbal devices b^2 , these parts being operated in alternation.

The operation of my toy amusement device will in the main be fully apparent from the above detailed description thereof. It will be further apparent that I have provided a drumming toy in which a number of movements is produced to effect a natural characterization of a syncopated or "jazz" drummer in action, all the movements being effectuated in a simple and harmonious fashion by mechanism which may be produced at a comparatively low cost. It will be further apparent that numerous changes

and modifications may be made in the construction and arrangement of the parts without departing from the spirit of the invention defined in the following claims.

5. I claim:

1. In a toy amusement device simulating a drummer in action, a support, a representation of a bass drum on the support, a figure representing a drummer arranged in sitting position on the drum, means independent of said figure for beating said drum, a simulated snare drum associated with the figure, means for beating the snare drum operated by movement of the figure, and mechanism for setting the figure in motion and for operating the first mentioned means in synchronization therewith to produce a simulated beating of the drums.
- 10 2. In a toy amusement device simulating a drummer in action, a casing defining a platform or stage, a representation of a bass drum on the platform, a figure representing a drummer arranged on said platform in sitting position on the drum, means independent of said figure for beating said drum, a simulated snare drum associated with the figure, means for beating the snare drum operated by movement of the figure, and mechanism housed by said casing and having parts extending through said bass drum and figure for setting the figure in motion and for operating the first-mentioned means in synchronization therewith to produce a simulated beating of the drums.
- 15 3. A toy amusement device for simulating a syncopated or "jazz" drummer in action, comprising a casing defining a platform or stage, a representation of a bass drum on said platform, a drum stick movable in relation thereto, a toy figure arranged in sitting posture on said drum and provided with movable arms, a representation of a snare drum associated with the figure, drum sticks carried by the arms and movable therewith in relation to the drum, and mechanism including a member extending vertically from said casing connected to said arms and drum stick for moving the same in synchronized action to effect a simulated beating of the drums.
- 20 4. A toy amusement device for simulating a syncopated or "jazz" drummer in action, comprising a toy figure provided with arms movable in opposite directions, a representation of a snare drum associated with the figure, drum sticks carried by the arms and movable therewith in alternation on the drum, a representation of a bass drum associated with the figure, a drum stick movable in relation thereto, the said figure being arranged in sitting posture on the bass drum, and mechanism including means extending through said casing, bass drum and figure and connected to the arms and drum stick for moving said arms and said drum

stick in synchronized action to effect a simulated beating of the drums.

5. A toy amusement device of the class described, comprising a casing defining a platform or stage, a representation of a bass drum on said stage, means for beating said drum, a figure representing a drummer having movable arms and a movable leg arranged on said platform in sitting position on the drum, the means for beating the drum being independent of said figure, a simulated snare drum carried by the figure, means for beating the snare drum operated by movement of the arms, and mechanism for setting the arms and leg on the figure in motion and for operating said first mentioned means in synchronization therewith to produce a simulated beating of the drums.

6. A toy amusement device of the class described, comprising a casing defining a platform or stage, a representation of a bass drum fixed on said stage, an oscillatable drum stick movable in relation to the drum for beating the same, a figure representing a drummer having movable arms and a movable leg arranged on said platform in sitting position on the drum, a simulated snare drum carried by the figure, the said movable arms on the figure carrying drum sticks movable in relation to the snare drum, and mechanism including a motor means housed by the casing for moving the said leg, for oscillating the said drum stick and for moving the said arms to produce a simulated beating of the drums.

7. A toy amusement device for simulating a syncopated or "jazz" drummer in action, comprising a toy figure adapted to be set in motion, representations of a snare drum and a trap implement associated therewith, means for beating the drum and playing the implement operated by movement of the figure, a representation of a bass drum associated with the figure, means for beating the same, and mechanism for setting the figure in motion and for operating the said means to produce a synchronized playing of the drums and the trap implement.

8. A toy amusement device for simulating a syncopated or "jazz" drummer in action, comprising a casing defining a platform or stage, a toy figure thereon adapted to be set in motion, representations of a snare drum and a trap implement associated therewith, means for beating the drum and playing the implement operated by movement of the figure, a representation of a bass drum on the stage associated with the figure, means for beating the same, and mechanism including a motor housed by the casing for setting the figure in motion and for operating the said means to produce a synchronized playing of the drums and the trap implement.

9. A toy amusement device for simulating a syncopated or "jazz" drummer in action,

comprising a casing defining a platform or stage, a toy figure thereon adapted to be set in motion, representations of a snare drum and a trap implement associated therewith, means for beating the drum and playing the implement operated by movement of the figure, a representation of a bass drum on the stage associated with the figure, means for beating the same, a sounding element in said casing, and mechanism for setting the figure in motion and for operating the said means and sounding element in synchronization.

10. A toy amusement device of the class described, comprising a casing defining a platform or stage, a representation of a bass drum on said stage, means for beating said drum, a figure representing a drummer arranged on said platform in sitting position on the drum, the said figure being provided with movable arms and a movable foot, a simulated snare drum carried by the figure, drum sticks carried by the arms of the figure and movable therewith in relation to the snare drum, a trap implement operated by movement of the said foot, and mechanism including a motor housed by the casing for operating the said means and for setting the said figure in motion to operate the snare drum and the trap implement in synchronization therewith.

11. A toy amusement device of the class described, comprising a casing defining a platform or stage, a representation of a bass drum on said stage, means for beating said drum, a figure representing a drummer arranged on said platform in sitting position on the drum, the said figure being provided with arms movable in alternation and with a movable foot, a simulated snare drum carried by the figure, drum sticks carried by the arms of the figure and movable therewith in alternation on the snare drum, a trap implement operated by movement of the said foot, and mechanism including a motor housed by the casing for operating the said means and for setting the said figure in motion to operate the snare drum and the trap implement in synchronization therewith.

12. A toy amusement device of the class described, comprising a casing defining a platform or stage, a representation of a bass drum on said stage, means for beating said drum, a figure representing a drummer arranged on said platform in sitting position on the drum, the said figure being provided with movable arms and a movable foot, a simulated snare drum carried by the figure, drum sticks carried by the arms of the figure and movable therewith in relation to the snare drum, a trap implement operated by movement of the said foot, mechanism including a motor housed by the casing for operating the said means and for setting the said figure in motion to operate

the snare drum and the trap implement in synchronization therewith, and a sounding element in said casing also operated by said motor.

13. In a toy amusement device simulating a syncopated drummer in action, a toy figure comprising a body having movable arms and a movable leg, representations of a drum and an implement associated with the figure, means for beating the drum operated by movement of the arms, means for playing the implement operated by movement of the leg, and mechanism extending through the body of the figure connected interiorly of the figure to said arms and leg for moving the same.

14. A toy amusement device of the class described, comprising a casing defining a platform or stage, a toy figure including a body having movable arms and a movable leg arranged in sitting posture on said stage, representations of a drum and an implement associated with the figure, means for beating the drum and playing the implement operated by movement of the figure, and mechanism extending through the body of the figure and connected interiorly of the figure to said arms and leg for moving the same.

15. A toy amusement device of the class described, comprising a casing defining a platform or stage, a toy figure having a body, movable arms and a movable leg arranged in sitting posture on said stage, a representation of a drum carried by the figure, drum sticks carried by the arms and movable therewith in alternation on the drum, a trap implement associated with the figure and operated by movement of said leg, and mechanism housed by the said casing and said body and connected to said arms and leg interiorly of the figure for moving said arms and leg in synchronization to produce a simulated playing of the drum and implement.

16. A toy amusement device for simulating a drummer in action, comprising a toy figure, said figure being provided with a body and with arms oscillatable in alternation thereon, a representation of a drum associated with the figure, drum sticks carried by the arms and movable therewith in alternation on the drum, and means for oscillating said arms comprising a pair of crank arms arranged in opposition within said body and connected respectively to said oscillatable arms, and a forked member connected to said crank arms and reciprocable within the body of the figure.

17. A toy amusement device for simulating a drummer in action, comprising a casing, a toy figure thereon, said figure being provided with a body and with arms oscillatable in alternation thereon, a representation of a drum associated with the figure,

drum sticks carried by the arms and movable therewith in alternation on the drum, and means for oscillating said arms comprising a pair of crank arms arranged in opposition within said body and connected respectively to said oscillatable arms, a

5 forked member connected to said crank arms

and reciprocable within the body of the figure and a motor housed by the casing for reciprocating said forked member.

Signed at New York city, in the county of New York and State of New York, this 20th day of March, A. D. 1923.

LOUIS MARX.
